FLAW DETECTOR FOR LOOMS

Andrew B. Shelton, Columbus, Ga., assignor to
A. B. Shelton Corporation, Columbus, Ga.

Application June 10, 1946, Serial No. 675,557

5 Claims. (Cl. 139—348)

1

The present invention relates to improvements in looms and more particularly to stop motions therefor.

One of the objects thereof is to provide a simple, efficient and inexpensive means for automatically stopping the operation of the machine upon the detection automatically of defects in the weave of the loom.

Another object thereof is to provide sturdy, dependable means for attachment to a part of the loom, so shaped, arranged and functioning that weak spots or other faulty areas of the cloth, being rolled upon the cloth roll of the loom, will be discovered, detected by mechanism that translates into action the means for stopping the loom. In this manner an opportunity is given to make corrections in the machine for overcoming the source of difficulties which caused the defects in the weave.

A still further object is to provide electrically controlled means for detecting defects in the texture of the cloth being woven on a loom or weaving machine to prevent serious trouble and breakdowns in the workings of the machine in a timely manner, and to overcome the cause of the defects in the weave.

Another object thereof is to provide novel means for closing an electric circuit to the usual electrical stop motion mechanism that effects stoppage of the loom which consists of mechanism for making a circuit closer responsive in operation to the action of a feeler which is in contact with the cloth being wound up on the cloth roll of the loom and which has been pre-set to be actuated automatically when the feeler comes in contact with defective portions of the advancing cloth.

A further object thereof is to provide a complete unit having means at one end by aid of which it can easily and quickly be mounted in correct position over the breast beam of the loom and arranged to have its feeler immediately brought into engagement with the cloth advancing towards the breast beam to the cloth roll, by virtue of which certain movable parts of a switch mounted upon the unit are pre-set for automatic operation when receiving a slight thrust due to engaging thin spots, etc., in the cloth.

Another object thereof is to provide a stop motion for a loom and similar weaving machine or textile apparatus which is characterized by the fact that it not only operates to render the machine inactive when engaged by a defective portion of the weave of the machine but also absorbs the impact of the lay as it is advancing towards the breast beam.

A further object thereof is to provide, in a device of the kind described, improved means for

2

automatically pre-setting the circuit closing parts of the device, the moment when the feeler finger thereof is caused to rest upon the material woven on the loom as it is moving upon the winding up cloth roll in a finished condition of weaving.

Another object thereof is to provide, in a device of the kind described, improved means for actuating the stop motion mechanism of the loom electrically, at the exact moment when a defective portion of the woven cloth moves into contact with the device, in spite of the fact that the device is subjected immediately afterwards to the impact of the advancing lay just before stopping of the machine occurs.

Another object of this invention is to provide, in a device of the kind described, improved means imparting to the device, when applied properly directly over the cloth roll, a yielding action when it is engaged and contacted by the lay of the loom as the latter, if performing its beating up operation upon the yarn, while simultaneously imparting to the circuit closing parts of the device automatic operation.

A further object is to provide, in a device of the character set forth, improved means whereby use is made of a movable contact member which serves the two-fold purpose of closing an electrical circuit for stopping the loom and of applying desirable spring pressure, at all time, for keeping the circuit closer under proper tension to stay in and out of contact with certain terminals.

With the above and other objects in view, my invention consists in the combination, arrangement and details of construction disclosed in the drawings and specification, and then more particularly pointed out in the appended claims.

In the drawings, wherein similar reference characters designate similar parts throughout the respective views,

Figure 1 is a side elevation of my invention, applied in use on a loom,

Figure 2 is a bottom plan view thereof,

Figure 3 is a longitudinal sectional view thereof,

Figure 4 is a sectional view taken on the line 4—4 of Figure 3, looking in the direction of the arrows,

Figure 5 is a section taken on the line 5—5 of Figure 3 looking in the direction of the arrows,

Figure 6 is a side elevation of a modified form of my invention,

Figure 7 is a bottom plan view of Figure 6,

Figure 8 is a fragmental detail view, partly in section, of the finger carried by the device shown in Figure 6,

Figure 8a is a fragmental detail view, partly

in section, of the pivoted end of the switch lever of the device illustrated in Figure 6.

Figure 9 is a cross section taken of the finger carried by the device illustrated in Figure 1.

Figure 10 is diagrammatic views illustrating the successive steps in the operation of the present invention upon a loom.

In the drawings, which are merely illustrative of my invention, all the parts thereof are made to appear. The present invention takes into consideration the requirements of a positive circuit closer for the circuit that operates the electrical loom stop motions which are now found on conventional looms electrically actuated. It further takes into consideration the supplying of as few parts as is consistent with simplifying the attachment, pre-setting thereof and actuation of the circuit closing parts of the device. It further bestows regard upon designing such a complete unit that it will enable it to withstand punishment, severe usage without the hazard of any parts becoming deranged or otherwise getting out of order.

In one form of my invention I provide a clevis upon a bracket and locate the circuit closing mechanism thereupon. The bracket is an L-shaped stamping or the like consisting of the right angularly disposed arms 10 and 11, formed both of them, with screw holes 12. This bracket is adapted to be surmounted upon the top 16 of the usual breast plate C of a loom, which is located in proximity to the cloth winding up roll B, over which cloth material woven on the loom, just beaten by the lay A thereof, is suitably stretched by the usual means. A screw bolt 13 is extended into each screw hole 12 of arm 11 of the bracket and into the breast beam part 16, its polygonal head 15 receiving the wrench for turning same down tight upon the bracket to clamp the latter against the breast beam 16.

The clevis 17 is a flanged metal body having the back bight portion 20 and the longitudinally oppositely extending side walls 18 and 19, forming flanges upon the top 18b of the clevis. The interior of the clevis is denoted at 21. In this interior 21 is located a contact carrier. The attaching bolt 13 passes through the screw hole 12 of arm 10 of the bracket and into the top 18b of the clevis, extends down the latter and receives a nut 14 as a means of clamping the clevis upon the bracket arm 10.

The clevis in this manner projects over the cloth roll B, as shown in Figure 1. The contact carrier in the clevis has the inner oppositely arranged arms 23, 24, formed with curved terminals 22 which hug the screw bolt 13 that attaches the clevis upon the bracket. The arms 23, 24, are offset from the base portions thereof which are in flat contact centrally of these members held riveted together as at 27. The opposite ends of the members of the contact carrier bulge out in opposite directions to provide holding arms 25, 26, that enclose with a spring pressure or otherwise an insulator block 29, the inner side of which contacts the top 18b of the clevis. From Figure 4, it will be seen that a kerf is cut into the block 29 into which the terminal 34 of an electrical wire 32 extends flatwise, so as to be clamped by a binding post 30 screwing home into the block and engaging the same for this purpose to imbed this terminal in the block insulatedly. The head of this binding post 30 is outside of the clevis, abuts the block 29, is designated 36, and constitutes a fixed contact.

The top 18b of the clevis is formed with a down-

wardly curving lip 35 which extends across between the sides of the clevis. The electrical wire 32 passes out of the clevis through a hole 28 in its outer end where the stretch 33 thereof runs to the stop motion circuit.

The underside of the block 29 is designated 37a. It is the side on which contact head 36 of the binding post 30 abuts. The bulging out portions 25, 26, of the contact carrier terminate in oppositely arranged cheeks 37, 37b, the forward edges of which are designated 45.

I provide a switch lever which is generally designated 40. It is a preferably channeled out metal body elongated in extent, having the longitudinally extending parallel walls 42, 43. The top of this lever is designated 41 and at its extreme inner end it is narrowed to provide a tongue 46 which is spaced from the adjacent ends 45a and 45b of the side walls of the lever 40, the latter forming a fork, while cheeks 37, 37b, of the contact carrier form another fork. The fork of the lever is pivoted in between the sides of the fork of the contact member, upon a pivot pin 44 passing into both forks. A pin 38 is mounted in the cheeks 37, 37b, eccentrically in advance of and below pivot 44. A collar 39 is loose on this pin and is interposed between lever 40 and the flat spring contact arm 46a.

The side walls 42, 43, of the switch lever 40 are formed with pairs of oppositely arranged integral lugs 47 upon the bottom thereof. These lugs are bent back under the lever and serve to clinch tightly upon the lever the inner secured tapering end 49 of a flat spring contact arm 46a. A collar 48 receives the parts of the lever 40 rigidly and rigidly and fixedly binds and secures the flat spring contact arm 46a between the ends of the lever 40, so this arm overlies the under edges of this lever.

A short length of a rod is telescoped and secured rigidly into the outer end of the lever 40, designated 50, being operatively grooved out at 50a by means of the opposite walls 51, 52. The outer ends of the side walls 51, 52, of this lever extension 50 are shaped to extend downwardly and rearwardly to provide oppositely arranged ears 53. A plastic finger 56 is provided formed at its inner end with an integral cam-shaped body 57, thickened out with respect to the finger proper. This body enters between the ears 53 of the lever extension 50 and is pivoted upon a pin 55 to these ears eccentrically thereof. The inner top edge of the finger is straight and at right angles to the axis of the finger, as shown at 58. A spring wire 59 has its inner portion extending into the lever 40 as shown in Figure 3 and bears against the top 41 thereof. It is formed with an integral intermediate crinkle 61, which abuts the end of the lever 40 proper, as upon a shoulder, at 63. The spring wire 59 extends in the lever extension 50 throughout its length and terminally it engages flat against the flat straight edge 58 of the cam 57 of the insulator or plastic finger 56. In doing this it causes this finger to depend from the outermost end of the switch lever at right angles to its length, yieldably, due to the presence of the spring wire 59. The edge 58 is the bottom of a recess 60 formed in the finger cam.

I provide a complete unit of my invention fully equipped with everything that functions as an electrical switch in Figures 1 to 5. I show a modified form of my invention in Figures 6 and 7. Here the unit is not complete in itself. It carries but one of the two contacts of the complete

switch, the other contact therefor being mounted upon the lay A of the loom. This modified unit will now be described.

This unit consists of a clevis and lever as hereinbefore set forth. The metal clevis has the bight portion 64 providing oppositely arranged arms 66, 67, and a top 65, which has a downwardly curving lip 65a terminally as shown in Figure 8A. The top 65 of the clevis has a screw hole 65b therein. The interior of the clevis is denoted at 68. A washer sleeve 69 acts to span apart the arms 66, 67, of the clevis, being mounted loosely upon a pintle 70 which passes through these arms and the longitudinally extending side walls 71, 72, of the switch lever about to be further described.

The switch lever is thus pivoted upon pintle 70 to the clevis. Mounted eccentrically of pintle 70 is another pintle 73 which also has its end confined into the arms 66, 67, of the clevis. Upon this last named pintle 73 is mounted loosely a roller 74 arranged at the lower plane of the clevis in its interior 68. A flat spring arm 76 is mounted rigidly upon a pair of clinched back lugs 80, 81, formed upon the opposite walls 78, 79a, of a guide member frictionally wedged or otherwise secured between the walls 71, 72, of the switch lever. This flat spring arm 76 is further seated upon clinched back lugs 77, formed directly upon the under edges of the last named walls 71, 72, of the lever. At one end thereof this flat spring arm 76 carries fast thereupon the forwardly projecting tab 75 which bears against the roller upon its under face. The other end of the flat spring arm 76 is frictionally held and bound upon the switch lever against the clinched back lugs integrally formed upon the sides 71, 72, of this lever. The extreme outer end of the flat spring arm 76 has a terminal 83 which is curvilinear in configuration. A pin 84 operatively projects through this curvilinear terminal 83 into the groove of the lever and serves as a stop for limiting the motion of a slide arm 79 guided movably over the outer end of the flat spring arm 76. This slide arm has a curved lip 80a moving therewith and abutting the stop pin 84, to prevent extraction of this slide arm from the lever.

The disposition of the clevis upon the lever is such that when the clevis is attached by a screw M Figure 6, directly upon the breast beam part 16, the lever will sag downwardly on a bias as shown in dotted lines in this figure, as well as in Figure 8A. The lever can only move upwardly on the clevis thus attached to the loom, to straighten itself out in line with the axis of the clevis, against the tension of the flat spring arm 76, the tab 75 of which will be pressed by the roller cam 74 and flexed, as the lever is thus manipulated.

The slide arm 79 has fixed to its outermost end, a reinforcing plate 85 and a U-shaped finger support is disposed below the arm 79 and fixed to the latter and the reinforcing plate 85 by a rivet 86. The support designated 87 includes a bight 88 and ears 89. A brass or conductor finger 91 is pivotally mounted on a pin 92 extending through the ears 89. A looped spring 96 is attached at its inner end to the slide bar 79 and has its forward end bearing against the upper end of finger 91 which is formed with a recess 93. A stop 94 extends upwardly from finger 91 and is held against the forward end of arm 79 by spring 96 so that the finger 91 will be normally disposed at substantially right angles to arm 79.

The use and operation of my invention is as follows:

Reference will be made to the diagram in Figure 10, as well as to the other figures of the drawing. Normally, when the clevis of either type of my invention is attached to the breast beam 16 of the loom, the switch lever 40 of the first type herein described extends longitudinally over the cloth 104 woven on the loom and passing over the winding up roll B, and passing over the lay A as shown. When the plastic finger 56 of the switch lever 40 is let down upon this stretched out cloth 104 so its tip end rests thereupon, as the cloth is advancing towards the breast beam, being lengthened by the beating process of the lay A, the finger is listed as a result. Initially, before this finger has been placed to rest upon the cloth, the lever 40 is raised upwardly as shown in dotted lines in Figure 3. When the finger 56 rests upon the cloth 104 of the loom, it has straightened out the lever 40 in line with the clevis. In Figure 10 there are shown the several positions of lever 40. The illustration at (a) Figure 10, shows the normal disposition of the lever upon the clevis, before the device is mounted upon a loom. The illustration at (b) shows the unit attached to a loom with the finger engaging the cloth 104 to raise the lever 40. In raising the lever in this manner, it is seen that there is a gap 105 between the free end of contact 46 and the fixed contact terminal 36. In Figure 1, it is seen that a wire 97 connects the lever 40 at its outer end. This lever is a good conductor of electricity. This wire is grounded at 98, also grounded, as at 99, is the wire 101 which connects with one side of a battery or electricity generator 100. From the other side of this battery a wire 102 extends, which with wire 103, which is attached to the contact screw 30 of the clevis, runs to the usual ground box (not shown), usually fastened down on the arch of the loom. It is here where the electrical means is caused, when the circuit is closed, to actuate the conventional loom stop mechanism.

In illustration (b) of Figure 10, it is intended to show that when the finger 65 resting upon the cloth 104, lifts the lever 40 to straightened out position, the free end of the spring contact arm 46a is in circuit breaking position. This is the normal loom operating setting of the lever. Should a thin spot or similar defect appear in the cloth as it advances to be fed over the cloth 50 roll B, when it comes under the finger 56, the finger, under influence of the springiness of the spring contact arm 46a (which had been put under tension upon raising of the lever), projects into the cloth which no longer can hold the 55 finger and lever up. The finger thus moves downwardly as indicated by the arrow in illustration (c) of Figure 10. Contact arm 46a is now in contact with contact 36, closing the electric circuit to the stop motion mechanism and stopping the 60 loom.

The modified device shown in Figures 6 and 7, operates in exactly the same manner as the device shown in Figures 1 to 5, except that the lay A carries one contact 105 which will engage contact finger 91 when the latter passes through the cloth and thereby close the stop motion circuit.

On the lay is secured an outwardly projecting spring finger or contact arm 105 having the lip 106. This arm is made integral with another arm 104 which is attached to the lay by the fastener 108. A terminal or binding post 107 attaches a wire 109 to this contact arm 104.

The electrical wire 109 runs to one side of the battery 110. From the other side of this battery 75 a wire 111, together with the wire 112 which is

attached at 113 to the clevis 64, connects to the loom stop mechanism as already described hereinbefore. This closes the circuit and stops the loom.

The present invention, in both forms, constitutes a positive contact making circuit closing device for stopping the loom to which it is attached. The device functions automatically and there is no occasion for parts to become deranged, or dislocated due to a minimum of friction existing and to the yieldable action of the switch lever when impacted by the lay. The device needs only a few screws to fasten down upon the loom, and it is then properly positioned and pre-set to close the electrical circuit of the loom stop motion mechanism when its finger feels the cloth and reaches a defect in the same.

I do not intend to confine myself to the exact details set forth herein save as pointed out in the appended claims.

What I desire to claim and secure by Letters Patent is:

1. A flaw detector for looms comprising an elongated lever, a lever supporting member for attachment to a loom, means pivotally mounting an end of said lever on said supporting member, an elongated flat spring on said lever secured at one end thereto, a spring engaging member on said supporting member offset from the pivot of said lever for engaging the free end of said spring thereby biasing the free end of said lever downwardly, a cloth engaging finger pivotally mounted on the free end of said lever normally supporting said lever against the spring tension, said lever constituting a conductor of a switch, a movable switch contact member on said lever, a fixed switch contact member, and means supporting said fixed contact adjacent an end of said lever in normally spaced relation to said movable contact whereby said movable contact will engage said fixed contact upon rocking of said lever under spring tension upon engagement of the finger with a flaw in the fabric.

2. A flaw detector for looms comprising an elongated lever for actuating an electrical switch connected to the stop motion of the loom, a lever supporting member for attachment to the loom, means pivotally mounting an end of said lever on said supporting member, a switch contact member on said lever, a fixed switch contact member adjacent an end of said lever, a fabric engaging finger on the free end of said lever, a flat spring on said lever and fixed at one end thereto, and a spring tensioning member on said lever supporting member engageable with the free end of said spring biasing said lever on the pivot thereof, said finger normally supporting said lever against the spring tension holding said switch contacts in spaced relation, said contacts engageable upon rocking of said lever under spring tension upon detection of a flaw in the fabric by said finger.

3. A flaw detector for looms comprising an elongated lever for actuating an electrical switch connected to the stop motion of the loom, a lever supporting member for attachment to the loom, means pivotally mounting an end of said lever on said supporting member, a switch contact member on said lever, a fixed switch contact member adjacent an end of said lever, a fabric engaging finger on the free end of said lever, a flat spring on said lever and fixed at one end thereto, a spring tensioning member on said lever supporting member engageable

with the free end of said spring biasing said lever on the pivot thereof, said finger normally supporting said lever against the spring tension holding said switch contacts in spaced relation, said contacts engageable upon rocking of said lever under spring tension upon detection of a flaw in the fabric by said finger, means pivotally supporting said finger on said lever, and spring means normally holding said finger perpendicular to the length of said lever.

4. A flaw detector for looms comprising an elongated lever for actuating an electrical switch connected to the stop motion of the loom, a lever supporting member for attachment to the loom, means pivotally mounting an end of said lever on said supporting member, a switch contact member on said lever, a fixed switch contact member adjacent an end of said lever, a fabric engaging finger on the free end of said lever, a flat spring on said lever and fixed at one end thereto, a spring tensioning member on said lever supporting member engageable with the free end of said spring biasing said lever on the pivot thereof, said finger normally supporting said lever against the spring tension holding said switch contacts in spaced relation, said contacts engageable upon rocking of said lever under spring tension upon detection of a flaw in the fabric by said finger, means pivotally supporting said finger on said lever, spring means normally holding said finger perpendicular to the length of said lever, the free end of said spring on said lever constituting the switch contact member on said lever, and means securing said fixed contact member adjacent the pivoted end of said lever.

5. A flaw detector for looms comprising an elongated lever for actuating an electrical switch connected to the stop motion of the loom, a lever supporting member for attachment to the loom, means pivotally mounting an end of said lever on said supporting member, a switch contact member on said lever, a fixed switch contact member adjacent an end of said lever, a fabric engaging finger on the free end of said lever, a flat spring on said lever and fixed at one end thereto, a spring tensioning member on said lever supporting member engageable with the free end of said spring biasing said lever on the pivot thereof, said finger normally supporting said lever against the spring tension holding said switch contacts in spaced relation, said contacts engageable upon rocking of said lever under spring tension upon detection of a flaw in the fabric by said finger, means pivotally supporting said finger on said lever, spring means normally holding said finger perpendicular to the length of said lever, said finger constituting the contact member on said lever, and means supporting said fixed switch contact member adjacent the free end of said lever for engagement with said finger upon detection of a flaw in the fabric.
